HUEBNER & WORREL
BY Richard M. Worrel
ATTY

Breadth $1\frac{3}{32}$ " to $1\frac{1}{16}$ ", average $1\frac{3}{16}$ ". Thickness $\frac{3}{4}$ " to $\frac{7}{8}$ ", average $\frac{13}{16}$ ".

Form.—Obovate.

Base.—Straight.

Apex.—Cuspidate.

Hilum.—Oval.

Sides.—Mostly unequal, rounded toward apex, flattened toward base.

Surface.—Irregularly furrowed and pitted throughout. Ridges—pronounced along dorsal edge, interrupted usually one or more times, pits circular and elongated. Dorsal edge—usually two ridges interrupted one or more times, discontinuous near apex. Ventral edge—thick with many small furrows.

Color.—Tan (11-C-6). Some red on both edges on many.

Tendency to split.—None.

Use: Market, local, dessert, culinary, long distance shipping.

Keeping quality: Good.

It is to be understood that normal variations in the

described characteristics of the new variety peach tree must be expected to result from environmental changes, such as in climatic and soil conditions, and from changes in cultural practices, such as in pruning, thinning, fertilizing, spraying, irrigating, and the like. The description is that of the variety produced under the ecological conditions prevailing at my farm at Red Bluff, Tehama County, California and the characteristics are found to hold true in asexual reproduction of the variety.

Having described and illustrated my invention, what I claim as new and desire to secure by Letters Patent is:

A new and distinct variety of peach tree substantially as described and illustrated, characterized as to novelty by the very red skin of the fruit while firm ripe, ripening about four days after Redhaven (unpatented) and about three weeks after Merrill Gemfree (Plant Patent No. 1,409), being similar to said Merrill Gemfree but being an improvement on that variety in its later ripening period and in the flesh being almost completely free from the stone when allowed to soften off of the tree.
